(57) **CLAIM**

The ornamental design for a steering wheel for an automobile, as shown and described.

DESCRIPTION

FIG. 1 is a front and left side perspective view of a steering wheel for an automobile showing my new design;

FIG. 2 is a front and right side perspective view thereof;

FIG. 3 is a front elevational view thereof;

FIG. 4 is a top plan view thereof;

FIG. 5 is a bottom plan view thereof;

FIG. 6 is left side elevational view thereof;

FIG. 7 is a right side elevational view thereof; and,

FIG. 8 is a rear elevational view thereof.

The broken lines in the drawings illustrate portions of the steering wheel for a automobile that forms no part of the claimed design
